(Cl. D52—3)

To all whom it may concern:

Be it known that I, Mario Caruso, a citizen of the United States, residing at Maplewood, in the county of Essex and State of New Jersey, have invented a new, original, and ornamental Design for a Vending Machine Cabinet, of which the following is a specification, reference being had to the accompanying drawing, forming part thereof.

Fig. 1 is a frontal perspective view of a vending machine cabinet, showing my new design;

Fig. 2 is a front elevation thereof;

Fig. 3 is a side elevation of Fig. 2; and

Fig. 4 is a top view of the cabinet.

I claim:

The ornamental design for a vending machine cabinet, as shown.

MARIO CARUSO.
